United States Patent

Des. 237,879

Patented Dec. 2, 1975

237,879

MAGNETISM AND INDUCTION EDUCATIONAL BOARD

Charles G. Valentine, Stamford, Conn., assignor to
Xerox Corporation, Stamford, Conn.

Filed Apr. 19, 1973, Ser. No. 352,794

Term of patent 14 years

Int. Cl. D19—07

U.S. Cl. D19—62

FIG. 2

FIG. 1 is a left perspective view of a magnetism and induction educational board showing my new design; and FIG. 2 is a right perspective view thereof.

The rear of the magnetism and induction educational board not shown is plain and unornamented.

I claim:

The ornamental design of a magnetism and induction educational board, substantially as shown and described.
